Primary Examiner — Mary Ann Calabrese(74) *Attorney, Agent, or Firm* — Sughrue Mion, PLLC(57) **CLAIM**

The ornamental design for a table as shown and described.

DESCRIPTION

FIG. 1 is a front and right perspective view of a table, showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is an enlarged cross sectional view of the portion defined by arrows 8 in FIG. 2, taken along the line 8-8' in FIG. 4.

FIG. 9 is an enlarged cross sectional view of the portion defined by arrows 8 in FIG. 2, taken along the line 9-9' in FIG. 4; and,

FIG. 10 is a front and right perspective view thereof with the top board in an alternate flipped up position of use.

The broken lines shown in the drawings illustrate portions of the table that form no part of the claimed design.
